UNITED STATES PATENT OFFICE.

LEO BLUHM, OF NEW YORK, N. Y.

DESIGN FOR A PRINTED FABRIC.

Application filed August 4, 1925. Serial No. 14,314. Term of patent 3½ years.

To all whom it may concern:

Be it known that I, LEO BLUHM, a citizen of the United States of America, and a resident of the city of New York, borough of Manhattan, in the county and State of New York, have invented a new, original, and ornamental Design for a Printed Fabric, of which the following is a specification.

Reference is to be had to the accompanying drawings, in which the figure illustrates a swatch of fabric having my new design printed thereon.

I claim—

The ornamental design for a printed fabric as shown.

LEO BLUHM.
